UNITED STATES PATENT OFFICE.

JASON C. STEARNS, OF WORCESTER, MASSACHUSETTS.

SPOT-LIGHT SUPPORT.

1,321,257.

Specification of Letters Patent. Patented Nov. 11, 1919.

Application filed January 25, 1919. Serial No. 273,153.

To all whom it may concern:

Be it known that I, JASON C. STEARNS, a citizen of the United States, residing at Worcester, in the county of Worcester and 5 State of Massachusetts, have invented a new and useful Spot-Light Support, of which the following is a specification.

This invention relates to a support for a spot light capable of use in many places 10 but designed especially for use in supporting a spot light from an upright or inclined frame or rod on an automobile.

The principal objects of the invention are to provide a construction suitable for use 15 either on an inclined or vertical supporting rod which will permit of the use of the spot light in the ordinary driving of the car so as to light up the road and yet permit it to be used for illuminating an elevated sign, but in both cases absolutely prevent throwing the light into the eyes of a 20 driver of an approaching car on the same level and also to permit a durable and permanent construction by which the lamp 25 can be detached from the support and used as a trouble lamp independent of the support and yet when put back will be found to be in the place for which it was designed. In other words the removal of the 30 lamp for that purpose will not necessitate any new adjustments and will not allow of the lamp getting out of position to accomplish the objects of the invention first set forth above. The invention also involves 35 features by which the construction is made strong and not likely to get out of order and it involves mechanism of a simple character not requiring mechanical experience for its operation, removal and replacement. 40 Further objects and advantages of the invention will appear hereinafter.

Reference is to be had to the accompanying drawings in which—

Figure 1 is a plan of a spot light shown 45 as supported on a vertical post or rod by mechanism constructed in accordance with this invention, parts being shown in section;

Fig. 2 is a front elevation showing parts 50 in section;

Fig. 3 is a view similar to the cross-hatched portion in Fig. 2 with the parts separated to permit removal of the spot light;

55 Fig. 4 is a face view of one of the elements shown in Fig. 3;

Fig. 5 is a perspective view of another element of the device;

Fig. 6 is a side view with the supporting screw in section showing the limitation of 60 the direction of the light when the spot light is in its normal position for running, and

Fig. 7 is a similar view showing the lamp 65 reversed and turned down to the lowest position possible.

The blinding of an approaching driver by the powerful lamps usually employed now-a-days on pleasure cars and the like is a public nuisance and must be done away with in some way. It has been found that 70 drivers cannot be relied upon to avoid this difficulty if they have means at hand that puts no check on them.

The principal object of this invention is to provide an exceedingly simple means by 75 which the spot light will be prevented from being turned into a position to blind an approaching driver and yet will be useful for all purposes for which a spot light can be used including its detachment so that it 80 can be used for a trouble lamp.

In order to accomplish these results and also insure that when the lamp is removed and replaced it will be put in the right place, I have shown the spot light casing 85 10 as mounted by any ordinary clamp 11 on an upright rod or bar 12 which as will appear hereinafter may be either vertical or inclined. As is usual the clamp 11 is provided with a swinging bracket 13 and this 90 has a circular flat projection 14 having a rounded or convex circular edge and provided with a radial slot 15 therethrough. This is made of sheet metal and the convexing of the projection 14 at its edges is an 95 important feature as will appear. This is designed to receive a screw connection 16 in the slot 15, a fixed head 17 being provided inside to form a stop against which to clamp the surface of the part 14 by means of an 100 adjusting and fastening nut 18. This is mounted to be adjusted along the screw 16.

The nut head is fastened permanently in position by the manufacturer and is not intended to be moved or adjusted except for 105 repairs, while the nut 18 is provided with a knurled edge and is intended to be operated by the user by hand.

The screw 16 passes into the lamp casing 110 10 radially and has a fixed flange 96 inside. The lamp casing can turn on the screw but that is provided with a washer

20 having a smooth surface engaging a similar surface on the hub of the lamp and having a radially toothed flat surface on its opposite side away from the lamp. An adjustable ring member 21 having a correspondingly shaped surface contacts with it, and a nut 24 is provided on the screw 16 for fastening the member 21 up against the washer 20 and permanently holding them together in their desired fixed relationship.

The member 21 is provided with a lug 22 coöperating with a fixed lug 23 on the lamp casing. The screw 16 is provided with two opposite flat surfaces 25 adapted to pass into the slot 15 through the center thereof. This is for the purpose of preventing the lamp being placed in the wrong position with respect to the bracket or yoke 13.

20. In the ordinary use of the device the screw 16 is inserted in the slot 15 into which it will pass as stated only when its flat sides are placed in the proper position. The head 17 passes in under the convex flat surface 14 as indicated more clearly in Fig. 2, and the screw 16 is thus fixed in position so that it cannot turn on its own axis. Now the nut 18 is turned up by hand so that a depression 26 in its wall will fit around and 25 clamp together the edges of the surface 14 and in that way the union of the lamp casing with the bracket 13 is fixed. It is to be observed at this point that any spreading of the edges of the slot 15 is absolutely prevented by the fitting of the convex surface 14 into the depression 26. These parts being clamped together as shown in Fig. 2 they are not only fixed so that the screw cannot turn, but any spreading of the walls 30 of the slot is effectively prevented, the pressure being applied to the convex edges of the surface 14 by the concave surface of the depression 26.

The screw 16 being fixed in that respect 45 it will be seen that as the nut 24 is screwed up tight by means of a wrench so that it exerts strong pressure on the ring members 21 and 20 and the adjacent surface of the hub 27 of the lamp casing, these parts 50 also are held firmly in position with respect to each other but the lamp casing itself being held only frictionally between the smooth adjacent surfaces of the hub 27 and the washer 20 can be turned on the axis of 55 the screw 16. Such turning is resisted by the frictional resistance so that the lamp will stay in any position to which it is turned. However, it will be seen that there is an important limitation to this turning: 60 The lug 22 as shown in Figs. 6 and 7 is fixed, but the lug 23 on the lamp is so located as to come into contact with this projection when the lamp is raised to its limiting position shown in Fig. 6. This lug 65 22 is intended to be so adjusted once for

all when the lamp is set up so that the spot light cannot be turned above the inclination indicated in Fig. 6. In other words, it cannot be turned in the direction opposite to that of the arrow in Fig. 6 to or 70 above the horizontal position and it cannot throw a direct light into the face of an approaching driver. If, however, the operator desires to turn the lamp up to see an elevated sign or the like, all he has to 75 do is to take hold of the handle and turn it in the direction of the arrow shown in Fig. 6 nearly all the way around, until it reaches its limiting position as shown in Fig. 7. Here again the lug 23 comes into 80 contact with the upper surface of the lug 22 and the light cannot be turned down into the eyes of an approaching driver. This turning in both directions is done without loosening any nuts or changing any 85 adjustments and these adjustments cannot be changed by hand.

If, however, it is desired to place this lamp on a car having a slanting rod 12 for supporting it instead of a vertical one a 90 wrench has to be applied to the nut 24 and the lug 22 adjusted differently for that usage. In cases where a lamp is to be made for a particular make of car this adjustment may be omitted, but it is an important 95 feature when the spot light is to be sold for use on all cars.

Of course it will be obvious that when it is desired to remove the lamp from the bracket and use it for a trouble lamp the 100 nut 18 is turned back by hand to the position shown in Fig. 3. This does not interfere with the adjustment of the lug 22 but it simply relieves the pressure between the head 17 and nut 18 and releases the lamp 105 from the bracket 13 so that it can be removed as a whole by drawing the screw 16 out of the slot 15 radially. The electrical wires of course pass through the screw 16 which is hollow and enough slack is provided so that the lamp can be used all 110 around the car as a trouble lamp or for finding articles in the road, or for any other purpose.

Now when it is desired to restore the lamp 115 to its normal position it has to be turned to such a point that the two flat sides 25 will pass into the slot 15 and then if the lamp has been applied right side around it will be found that the adjustment and limitations indicated in Figs. 6 and 7 are retained absolutely without any change. There are only two positions in which it 120 can be placed, one in the exact position shown, and the other with the lamp pointing to the rear, the latter being a mistake which nobody is likely to make.

In this way it will be seen that the above mentioned objects are accomplished, the light cannot be thrown into the face of an 125 130

approaching driver either when the spot light is being used in the regular course of travel, or when it is being turned up to look at a sign, nor can it be while changing from 5 one of these positions to the other. Furthermore, the removal of the lamp for other uses is simple and convenient and its replacement equally so with no danger of its being put back in the wrong place or its 10 adjustment being lost by the change; no tools are required for the uses which the lamp is to be put by the driver; and no changes can be made in the adjustment without the use of tools. However, the lamp is 15 so designed that it can be used whenever desired upon a different type of car by making adjustments for which a wrench is of course required.

Although I have illustrated and described 20 only one embodiment of the invention I am aware of the fact that modifications can be made therein by any person skilled in the art without departing from the scope of the invention as expressed in the claims. 25 Therefore I do not wish to be limited to all the details of construction herein shown and described, but what I do claim is:—

1. The combination with a spot light casing and a supporting bracket, of a screw 30 connection between the bracket and spot light casing, about the axis of which the spot light casing is adapted to be turned, a circumferentially adjustable ring member on said screw having a limiting lug, a lug 35 located on said casing in position to engage the first named lug when the casing is turned, and a nut on the screw for fixing the ring member in adjusted positions.

2. The combination with a supporting 40 bracket, of a spot light casing, and a straight connection between them extending radially from the casing, means on said connection for detachably connecting it with the casing to allow the spot light casing to be turned 45 about the radial axis of said connection independently of the bracket, a limiting lug carried by said means and adjustable about said radial axis independently of the casing, and means on the casing adapted to engage 50 said lug when the casing is turned on said radial axis, whereby such turning motion of the casing is limited.

3. The combination with a supporting bracket, of a spot light casing, a connection between them about the axis of which the 55 spot light casing is adapted to be turned, a limiting lug, a lug on the casing adapted to engage the first named lug when the casing is turned, and readily detachable means for securing said connection to the bracket 60 and removing it therefrom without disturbing the relative positions of said lugs, whereby the connection and lamp casing can be removed from the bracket to permit the lamp to be used as a trouble lamp without 65 changing the relative adjustment of said lugs.

4. The combination with a bracket, a spot light casing, and a connection between them in the form of a screw arranged with its 70 axis perpendicular to the surface of the casing from which it projects, of a nut on the opposite end of said screw for detachably fastening the screw to the bracket, and a fixed head on the end of the screw 75 most remote from the casing adapted to fit behind the surface of the bracket against which said nut presses for fastening the parts together.

5. The combination with a bracket having 80 a radial opening through its side and provided with a flat surface with a convex edge substantially surrounding said radial slot, a screw extending through said slot, a lamp casing supported by said screw, and a nut 85 on the screw provided with a concave surface fitting the convex edge surface of the bracket for preventing the spreading of the sides of said slot under pressure.

6. The combination with a bracket, a spot 90 light casing, and a connection between them in the form of a screw, said bracket having a flat surface with a convex edge and provided with a radial slot opening through its side, said connection having flattened 95 walls adapted to fit in said slot to prevent turning of the connection when applied to the bracket, of a nut provided with a concave surface fitting the convex edge surface of the bracket for preventing the spreading 100 of the sides of said slot under pressure.

In testimony whereof I have hereunto affixed my signature.

JASON STEARNS.
